(57) **CLAIM**

The ornamental design for a tablet computer, as shown and described.

DESCRIPTION

1. Tablet computer

1.1 : Front

1.2 : Back

1.3 : Left

1.4 : Right

1.5 : Top

1.6 : Bottom

1.7 : Perspective

1.8 : Perspective

1.9 : Perspective view in a state of use

1.10 : Perspective view in a state of use

1.11 : Perspective view in a state of use

The figures include surface shading, which represents contour and not surface ornamentation; the broken lines in the figures illustrate features that form no part of the claimed design; the additional broken lines in figure 1.11 depicting a pen illustrate environmental subject matter that forms no part of the claimed design.

1 Claim, 11 Drawing Sheets
